UNITED STATES PATENT OFFICE

FRITZ HARTMANN, OF RHEINHAUSEN (LOWER RHINE) -FRIEMERSHEIM, GERMANY,
ASSIGNOR TO FRIED. KRUPP AKTIENGESELLSCHAFT, FRIEDRICH-ALFRED-HUTTE,
OF RHEINHAUSEN (LOWER RHINE), GERMANY

IRON SLEEPER

Application filed February 24, 1932, Serial No. 594,900, and in Germany May 15, 1931.

This invention relates to iron sleepers and is particularly applicable to railway sleepers. The invention is concerned with that kind of sleeper in which the rail foot is held between transverse ribs and consists in providing each rib on the side remote from the rail foot with an opening for the reception of the rail-fixing means, and in forming the rib so that it runs taperingly into the surface of the sleeper on the same side as the opening is formed. Preferably each rib also runs gradually into the surface of the sleeper at the sides thereof.

In order that the invention may be clearly understood and readily carried into effect, one construction in accordance therewith will now be described by way of example with reference to the accompanying drawing, in which

20 Figure 1 shows a central longitudinal section through part of the sleeper.

Figure 2 is a plan thereof partly in section, and

25 Figures 3 and 4 are sections on the lines III—III and IV—IV respectively of Figure 1.

The sleeper 2 is formed at those parts which are intended to support the rails with two ribs 3 spaced a small distance apart and 30 having walls which are approximately vertical and are parallel to the outer surface of the foot 4 of the rail 1. These ribs are higher than the rail foot at the center of the upper surface of the sleeper but become gradually 35 lower towards the inclined surfaces 6 of the sleeper, and finally run into these surfaces as is shown particularly in Figures 3 and 4. In the longitudinal direction of the sleeper the ribs 3 run on the side remote from the rail foot 4 gradually into the sleeper surface proper 5 or the inclined surfaces 6 by means of slightly inclined or tapered surfaces 7 and 8. In the direction of the central longitudinal axis the horizontal upper sleeper surface 45 5 enters between the inclined surfaces 8 by means of a tongue as it were, with the result that a recess or chamber 9 having side walls 18 is formed. The tongue portion of the sleeper surface 5 runs into a steep wall 10 which is parallel to the rail 1 and which closes

the end of the chamber 9. A horizontal bridge 11 forming part of the rib joins on to this wall 10. The ribs 3 with the walls 10 and the bridges 11, and the inclined surfaces 7 and 8 with the side walls 18 are pressed out of the sleeper by means of suitable apparatus in the course of the manufacture of the sleeper.

In the bridge 11 there is an elongated hole 12 which, in the direction of its longitudinal axis, extends to the said tongue portion of the sleeper surface 5. This hole serves for the insertion of a holding bolt 13. The head 14 of this holding bolt is formed with a cylindrical or spherical surface 15 which corresponds to the bearing surface 16 on the underside of the bridge 11. The nut of the holding bolt bears preferably through a resilient washer on a clamping plate or clip 17 which bears against both the bottom of the chamber or recess 9 and against the rail foot 4.

The clamping plates or clips 17 are fixed in position longitudinally of the rail by means of the vertical walls of the ribs 3. The cylindrical or spherical bearing surface in the 75 inside of each rib and the engagement therewith of the correspondingly shaped bolt head 14 ensure permanently uniform bearing of the clamping bolts on the sleeper, and thus the rail fixing is stressed uniformly by the 80 forces which are set up here. Further, owing to the fact that the outer foot of the clamping plate or clip 17 lies within the chamber or recess 9, any transmission of the thrust due to creeping of the rail to the edge of the 85 hole 12 by way of the clamping bolt is avoided, and on the contrary that thrust is taken by the pressed-out walls 18 of the chamber 9, that is to say by the whole sleeper material.

90 What I claim is:

1. An iron sleeper having transverse ribs adapted to determine the lateral position of the rail foot, each of these ribs being provided on the side remote from the rail foot 95 with an opening for the insertion of the rail fixing means and on the same side gradually tapering away so that its surfaces run into the surface of the sleeper in the longitudinal direction of the latter.

2. An iron sleeper having transverse ribs adapted to determine the lateral position of the rail foot, each of these ribs being provided on the side remote from the rail foot with an opening for the insertion of the rail fixing means and on the same side gradually tapering away both in the longitudinal and transverse direction of the sleeper into the surface of the latter.
- 10 3. An iron sleeper having transverse ribs adapted to determine the lateral position of the rail foot, each of these ribs being provided on the side remote from the rail foot with an opening for the insertion of the rail fixing means and on the same side gradually tapering away so that its surfaces run into the surface of the sleeper in the longitudinal direction of the latter, a steep wall portion being formed in said inclined surfaces adapted to form together with the top wall of the rib and the wall thereof turned toward the rail foot a bearing for the head of the rail fixing bolt, said bearing having supporting surfaces for said bolt head adapted to the shape of the latter.
- 15 4. An iron sleeper having transverse ribs adapted to determine the lateral position of the rail foot, each of these ribs being provided on the side remote from the rail foot with an opening for the insertion of the rail fixing means and on the same side gradually tapering away so that its surfaces run into the surface of the sleeper in the longitudinal direction of the latter, a steep wall portion being formed in said inclined surfaces adapted to form together with the top wall of the rib and the wall thereof turned toward the rail foot a bearing for the head of the rail fixing bolt.
- 20 5. An iron sleeper having transverse ribs adapted to determine the lateral position of the rail foot, each of these ribs being provided on the side remote from the rail foot with an opening for the insertion of the rail fixing means and on the same side gradually tapering away so that its surfaces run into the surface of the sleeper in the longitudinal direction of the latter, a steep wall portion being formed in said inclined surfaces adapted to form together with the top wall of the rib and the wall thereof turned toward the rail foot a bearing for the head of the rail fixing bolt, said opening having an elongated shape and being provided in said top wall and said steep wall portion as well as in that part 35 of the sleeper surface proper which is adjacent to said steep wall portion.
- 30 6. An iron sleeper having transverse ribs adapted to determine the lateral position of the rail foot, each of these ribs being provided on the side remote from the rail foot with an opening for the insertion of the rail fixing means and on the same side gradually tapering away so that its surfaces run into the surface of the sleeper in the longitudinal direction of the latter, a recess in each rib adapted to form a chamber for the one leg of a rail fixing clip, said recess extending down to the surface of the sleeper proper and being formed by three steep walls interrupting said tapering surfaces, said opening having an elongated shape and being provided in the top wall of the rib and that of said steep wall which runs in parallel with the rail as well as in the part of the sleeper surface adjacent to said last-named steep wall.
- 35 7. An iron sleeper having transverse ribs adapted to determine the lateral position of the rail foot, each of these ribs being provided on the side remote from the rail foot with an opening for the insertion of the rail
- fixing means and on the same side gradually tapering away so that its surfaces run into the surface of the sleeper in the longitudinal direction of the latter, a steep wall portion being formed in said inclined surfaces adapted to form together with the top wall of the rib and the wall thereof turned toward the rail foot a bearing for the head of the rail fixing bolt, said bearing having supporting surfaces for said bolt head adapted to the shape of the latter.
